PAPER END INDICATOR FOR TYPEWRITERS

Giuseppe Prezioso, Yverdon, Switzerland, assignor to E. Paillard et Cie S. A., a corporation of Switzerland

Application August 7, 1941, Serial No. 405,876
In Switzerland February 6, 1941

6 Claims. (Cl. 197—189)

It has been found of utility in typewriters to provide some form of device capable of giving an audible or a visible signal when the end of the sheet being fed around the platen in the course of typewriting is about to be reached, particularly in view of the ever increasing swiftness of typewriting work. Devices proposed heretofore to that effect are not fully satisfactory because the signal thus given is either only audible or only visible. Besides, such known devices have been specially adapted for being fitted to existing typewriters, which necessarily involves a large overall structure which is not convenient and does not properly fulfil its function because the requirements often contradict the normal features of the typewriter. Thus, for example, devices of this kind have been proposed which require a shortening of the length of the platen or cylinder. Other devices as proposed do not permit the platen to be properly and freely manipulated by its two end operating knobs. Still other devices of this kind require additional handling when a new sheet is being inserted even when the signalling means is not utilised. Lastly it has been found in practice that it is absolutely necessary for the platen to always remain free for rotational movements so as not to hinder the typist's work.

An object of the present invention is to provide an improved device or mechanism for giving both an audible and a visible signal when the bottom end of the paper or other sheet being typewritten is about to be reached, this device being specially constructed for obviating the aforesaid disadvantages while acting at the same time as an indicator of the starting position of the platen and also of the sheet inserted between the platen and its adjacent rolls, said indicator indicating such position in a conspicuous way and being adjustable so as to match any given length of sheet so that with paper sheets of different sizes such for example as the conventional foolscap, crown or demy sizes, timely actuation of the signalling means is insured when the bottom end of the sheet is approached.

Another object of the invention is to provide a warning and indicating device of this class wherein the adjustment of the sheet inserting position indicator can be readily performed by a mere counter-clockwise rotation of the platen prior to actual sheet insertion and said indicator bears marks connoting different conventional paper lengths.

Another object of the invention is to provide a warning and indicating device of this class wherein both, the signalling means for giving a

visible warning when the bottom end of the sheet being typewritten is about to be reached and the sheet inserting indicator are in the form of angularly displaceable members, advantageously of sectors, barrels or drums loosely revoluble on the platen axle and bearing index scales showing through apertures in the front wall of the typewriter housing so as to be clearly visible.

10 A further object of the invention is to provide a warning and indicating device of this class, wherein proper inserting feed of the sheet between the platen and its companion rolls is facilitated by a hand actuator, advantageously a crank loosely fitted on the stub axle of the one element of a gear normally driven by the platen and provided with the members which trip the signalling means into operation, declutching means interposed between said actuator and gear preventing undue interference with the normal rotation of the platen as typewriting proceeds.

15 A further object of the invention is to provide a warning and indicating device of this class, wherein the actuator stroke can be easily adjusted by accurate setting means, advantageously comprising an abutment associated with a micrometric screw and bearing a scale for cooperation with an index line.

20 A further object of the invention is to provide a warning and indicating device of this class, wherein the operation of the members associated with the gear driven by the platen and tripping the signalling means cannot be disturbed by any motion imparted to the platen and said means are always reliably actuated at the proper position as preselected by the sheet inserting and platen start indicator.

25 Still a further object of the invention is to provide a warning and indicating device of this class made up of a small number of simple and rugged parts easy to make and to assemble and having such a structure as to keep the platen clear of hindrances so that proper operation thereof is just as sure as in an ordinary typewriter devoid of such a device.

30 40 45 50 55 With these and such other objects in view as will incidentally appear hereinafter, the invention comprises the novel construction, combination and arrangement of parts that will now be described in detail with reference to the accompanying diagrammatic drawing exemplifying the same in a non-limitative manner and forming a part of the present disclosure.

In the drawing:

Figure 1 is an isometric view partly showing the device whose elements placed in different

planes are separated for the sake of clearness, assuming certain parts to be broken.

Figures 2 to 5 are fragmentary views showing constructional details.

As shown by Fig. 1, a pinion 1 rigidly mounted on the stub axle 2 of the platen or cylinder 3 is in mesh with a much larger toothed wheel or master gear 4 which freely revolves on an axle 45 mounted in a carrier 7 rigidly secured to the typewriter frame. The toothed wheel or master gear 4 carries the operating members adapted to trip the audible and visible signalling means into action. In the embodiment which is illustrated, such operating members are constituted by studs 5, 6 adapted to engage the actuating members of the signalling means. In order to permit rotation of the platen in both directions, said actuating members are adapted to be tripped for working the signalling means only when they are engaged in one direction (the one corresponding to the feed of the sheet) by said studs but not in the opposite direction.

For this purpose, the actuating member for the signalling means which gives an audible warning of the proximate reach of the bottom end of the sheet comprises an arm 8 pivoted to a suitable part of the frame and connected to the hammer 9 of a bell 13 (Fig. 5). The arm 8 is provided with a tongue 11 and has pivoted thereto a lever 10 which is urged into contact with the tongue 11 by a spring 12.

The actuating member for the means giving a visual signal comprises a cranked lever 14 loosely mounted on the platen axle 2 and having a tongue 15 (Fig. 4). A retracting spring 17 urges the lever 14 to a position in which its tongue 15 is engaged with an arm 15a integral with a sector pivoted on the axle 2. This sector carries a barrel or drum 16 one portion of which is visible through an aperture in a housing 19 which encloses and protects the whole mechanism. The drum 16 is urged into the position of rest shown in the drawing by a tension spring 21. An abutment 21a firmly secured to the housing 19 determines this position of rest. A scale is engraved on the surface of the drum 16 for cooperation with an index line 20 on the housing 19. The purpose of this scale is to indicate to the typist the amount of lower free marginal space which remains utilizable at the bottom end of the sheet after the audible signal has been given.

As shown in Figs. 2 and 3 which illustrate on a smaller scale the toothed wheel or master gear 4 and its studs 5, 6, the studs 6 are at a lesser distance from the centre of the wheel or master gear 4 and have a greater length than the studs 5 arranged near the periphery of said wheel or master gear 4, whereby each of the studs 5, 6 actuates only the operating member related to it.

On the toothed wheel or master gear 4 is rigidly secured a cog wheel 21 which through a second cog wheel 23 actuates a third cog wheel 24 loosely mounted on the stub axle 2. The diameters of these wheels are such that the angular motions of the cog wheel 24 are exactly equal to those of the toothed wheel or master gear 4. The wheel 24 has fixed thereto a barrel or drum 25 which moves across an aperture in the housing 19 opposite an index line 26. On the surface of the drum 25 is engraved, painted or otherwise marked a scale showing the angular positions to which it should be set (in accordance with the length of the sheet) before the

sheet is inserted between the platen and its companion rolls, so that the audible signal will be given when the remaining space at the bottom of the sheet corresponds with the greatest margin indexed on the drum 16 for giving a visible signal. Therefore the drum 25 is an indicator of the starting positions of the platen for varying sizes of sheets such for example as the conventional foolscap, crown or demy sizes.

Between the toothed wheel or master gear 4 and the cog wheel 21 is interposed a ratchet wheel 28. A sector 29 and a crank 30 are freely pivoted on the end of the axle 45 which carries the toothed wheel or master gear 4. The crank 30 is positioned externally of the housing 19 and actuates the sector 29 by means of a pin 31 provided upon the latter and received in a slot 32 in the crank hub.

The sector 29 is urged to a position of rest by a spring 33 (as shown in the drawing). A pawl 35 pivoted to the sector 29 has teeth 36 which come into engagement with the teeth of the ratchet wheel 28 under the action of a spring 37. The position of rest of the sector 29 is determined by a bracket abutment 39 secured to the inner wall of the housing 19 and upon which rests the horn-shaped end 38 of the pawl 35. The latter is then held clear of the ratchet wheel 28.

An upward extension or nose 41 of the pawl 35 limits the rocking movement of the sector 29 when it is driven by the crank 30 by coming into contact with an adjustable abutment 40. The latter is secured to a micrometric screw 42 fitted with a knob 42a and journaled in the side wall of the housing 19. The abutment 40 can slide through a slot in the top wall of the housing 19 along a stationary scale 44. The upper face of the abutment 40 has engraved thereon an index line 43. From the scale 44 may thus be read off the value of the upper marginal space of a sheet which is attained when the sheet is brought into a typing position by rotation of the crank 30 until the nose 41 of the pawl 35 engages the abutment 40.

The operation of the device is as follows:

First, if it is desired that the first line to be typed on a sheet shall be spaced a definite distance downward from the top of the sheet, the index line 43 on the abutment 40 is registered with the index of the scale 44 which corresponds with the value of the upper marginal or caption space that it is desired to obtain. As the adjustment of the abutment 40 is performed by operating the micrometric screw 42 by means of its knurled knob 42a, the possibility is afforded of very accurately adjusting the position of said abutment and of selecting said upper marginal space so that the first line to be typewritten may, for example, be properly positioned relative to a date line of a letter or report. Next, depending upon the length of the sheet to be used, the platen 3 is rotated counter-clockwise until the index on the drum 25 corresponding to the length of sheet to be used is brought into register with the index line 26.

The gear ratio between the toothed wheel or master gear 4 and the cog wheel 24 being equal to 1, said wheel 24 revolves much more slowly than the platen 3. Actually the revolution of the drum 25 is exactly the same as the toothed wheel or master gear 4 and its angular motion therefore corresponds with that of the operating studs 5, 6. Consequently the indicator drum 25 makes it possible to readily bring the platen angularly

speaking to such a starting position that the audible signalling means shall be efficaciously actuated exactly at the time when the lower marginal space corresponds to the greatest margin as indexed on the drum 16 of the means for giving a visible signal and from that exact time said drum 16 shall be so actuated as to indicate, as the platen moves, the lower marginal space which is still available.

Upon completion of these two adjustments, the sheet is slid along the paper shelf (not shown) so as to bring the upper edge of this sheet into engagement with the rearwardly located gripping rolls. It is then only necessary to rotate the crank 30 counter-clockwise against the action of the spring 33 until the nose 41 comes into contact with the abutment 40 for bringing the sheet to the position selected for beginning to typewrite. At the outset of this motion, the horn 38 on the pawl 35 snaps off the abutment 39, whereupon its teeth 36 are urged by the spring 37 into engagement with the teeth on the ratchet wheel 28. As the latter is connected to the toothed wheel or master gear 4, the motion of the crank 30 is transmitted to said toothed wheel or master gear 4 and also to the platen 3, which engages the sheet resting upon the paper shelf. When the pawl nose 41 contacts the abutment 40, the sheet therefore occupies the desired position and is ready for typewriting. Upon release of the handle 30 the spring 33 returns the sector or segment 29 and the pawl 35 to normal position thereby causing the arm 38 of said pawl to engage with the abutment 39 against the tension of the spring 37 thereby lifting ratchet teeth 36 so that they 35 will be in a position to properly engage with the ratchet gear 28 on the next forward movement of the handle 30.

The platen 3 is then moved either by means of its operative knob or by the line space lever of usual construction (not shown). When the lower marginal space which is still available will only represent for example 3" (corresponding to the largest lower margin as indexed on the drum 16) the means 8 to 13 for giving an audible signal will be operated, and the stud 5 carried by the toothed wheel or master gear 4 will come into engagement with the lever 14 of the means for giving a visible signal. Following this, a portion of the warning drum 16 (which may be for example painted red) will show through an aperture in the housing 19. This will give a permanent and gradual warning of the reduction of the lower marginal space on the sheet, as set out say in inch fractions or in millimeters by the index scale engraved on said drum 16 opposite the mark line 20.

It will be seen that as the toothed wheel or master gear 4 exactly follows all the motions of the platen 3, the latter can be conveniently turned clockwise or counter-clockwise without any risk of the signalling means being disturbed in their operation.

Moreover, the large reducing ratio between the pinion 1 and the toothed wheel or master gear 4 permits the first line to be typewritten to be brought down a substantial distance from the upper edge of the sheet merely by imparting to the crank 30 a relatively small angular motion.

Another advantage is that no stationary abutment hinders the motions of the typewriter platen. This is imperatively required because nothing is more unpleasant in a typewriter than a platen which becomes jammed in the course of typewriting. Still another advantage is that the starting positions for the platen to match the

varying size of the sheets that may be used can be easily and rapidly adjusted owing to the indicator which reproduces the movements of the toothed wheel.

For reasons of convenience and accuracy, the constructional embodiment of the invention which is shown in the drawing comprises a toothed wheel or master gear 4 having a relatively large diameter, so that the platen motion which is necessary for properly rolling through a sheet having the longest length to be found in commercial practice should not cause an angular displacement exceeding half a revolution of the toothed wheel or master gear 4. It thus becomes possible to provide two pairs of diametrically opposed studs 5, 6. As a result of this, the operating members for the means giving the audible and visible signals respectively can be simply offset by 180°. This arrangement makes it possible to provide the means for giving the visible signal adjacent the front side of the typewriter and the means for giving the audible signal adjacent its rear side.

Obviously the studs 5 might be situated on a diameter different from the one on which the studs 6 are located. It would only be necessary for that purpose to correspondingly locate the actuators for the signalling means.

If several pairs of studs 5 and 6 are to be used, the gear ratio between the toothed wheel or master gear 4 and the cog wheel 24 may be different from 1:1. It should not, however, exceed the number of stud pairs provided on said toothed wheel.

It is advantageous, generally speaking, to provide between the toothed wheel or master gear 4 and the cog wheel 24 such a gear ratio that an angular motion of said wheel 4 corresponding with the setting angle of the several studs 5, 6 should cause a rotation of one revolution or a fraction of one revolution of the indicator drum 25. It thus becomes possible to repeat on the periphery of the indicator drum 25 the scale which indicates the starting positions of the platen as many times as the number of sectors comprised in said drum corresponding with an angular motion of the toothed wheel or master gear 4 equal to the angular setting of the studs.

In order that the visual indicating means should be clearly visible, it is preferable that the aperture in the housing 19 should be provided in the front face of said housing approximately level with the line on which typewriting takes place.

The constructional details of the above-described device or mechanism might vary of course without departing from the scope of the subjoined claims.

What is claimed is:

1. In a typewriter, the combination including, a platen and a platen shaft mounted for rotatable sheet feeding movement, a sheet starting indicator, a pinion fixed on the platen shaft, a master gear meshing with said pinion, a gear train connecting said starting indicator with the master gear whereby said starting indicator and master gear move in step by step relation, manually operated means for initially moving said platen and master gear through a part of their respective cycles and also correspondingly move said starting indicator through said gear train, a sheet end indicator, and means on the master gear for actuating said sheet end indicator as the sheet approaches the end of its travel over the platen.

2. In a typewriter, the combination including, a platen and a platen shaft mounted for rotatable sheet feeding movement, a sheet starting indicator drum, a pinion connected with the platen, a master gear meshing with said pinion, reduction gearing between said starting indicator drum and said master gear to move the same in step by step relation, crank actuated clutch means for moving said master gear through a portion of its cycle, a sheet end indicator, and means on the master gear for operating said sheet end indicator as the platen moves the master gear under line spacing incident to typing the full sheet.

3. A sheet indicator device for typewriting machines for initially moving the sheet to selected typing position and subsequently indicating the approach of the end of the sheet, comprising, in combination, a platen, a platen shaft, a pinion fixed to said shaft, a sheet end indicator, a master gear meshing with said pinion and having a pin thereon for actuating said sheet end indicator, a sheet starting indicator drum geared to the master gear and adapted to be set at starting position upon rotating the platen counterclockwise, and crank controlled clutch means for initially moving the master gear and starting indicator drum.

4. In a typewriter, the combination including, a platen and a platen shaft mounted for rotatable paper feeding movement, a casing including top and end walls, a sheet starting indicator drum, a pinion fixed on the shaft of the platen, a master gear meshing with said pinion, a gear train connecting said starting indicator with the master gear whereby said starting indicator and master gear move in step by step relation, means for initially moving said platen and master gear through a portion of their respective cycles and also correspondingly move said starting-position indicator drum, said means comprising a pair of abutments located on the top and end walls of the casing, said abutment on the top wall being adjustable, a clutch device including a sector and a ratchet wheel mounted coaxially with the master gear, a lever pivoted to the sector and having means intermediate its ends for engaging said ratchet wheel while its ends are adapted alternately to engage said abutments, and a crank operatively connected with said sector whereby movement of said crank in one direction will cause the clutch means to engage the ratchet to move the master gear through a portion of its cycle and in turn move the pinion and platen sufficiently to cause the platen to draw the sheet to the position of the first line to be typed and at the same time register sheet travel on the starting-position drum, a sheet end indicator, and means on the master gear for actuating said sheet end indicator to connote the approach of the end of the sheet, said platen, master gear and starting-position indicator drum being returned to starting position by rotation of the platen after the sheet has been removed.

5. An indicator device for typewriting machines for indicating the approach of the end of the sheet around the platen, comprising, in combination, a platen roller, a platen shaft for manual and mechanical operation, a casing secured to

the frame of the machine and having a pair of spaced windows each provided with gauge marks on an edge thereof, a sheet end indicator segment loosely mounted on the shaft behind one of said

5 windows and having scale marks for cooperation with the gauge marks thereon, a sheet starting indicator drum also loosely mounted on the shaft behind the other of said windows and having scale marks thereon for cooperation with the gauge marks thereon, a pinion rigid on the shaft, a master gear supported for rotary movement in the casing and meshing with said pinion, means on said gear for actuating said sheet end indicator segment for a part of its cycle of movement, a reduction gear train for moving said drum in step with the master gear, a ratchet wheel in coaxial fixed relation to the master gear, a segment loosely mounted on a shaft coaxial with the ratchet gear and normally spring tensioned toward inoperative position, an adjustable abutment on the top wall of the casing, a fixed abutment on the rear wall of the casing, a ratchet lever pivoted to the segment and having teeth intermediate its ends and a nose at one end adapted for engaging said adjustable abutment and also having a nose at the other end for normally engaging said fixed abutment, a spring between the lever and the segment for biasing the lever toward the fixed abutment thereby to maintain the teeth of said lever out of engagement with the ratchet gear, a crank mounted coaxially with the ratchet gear and coupled with the segment, said crank when moved against the spring effort imposed on the segment moving said ratchet lever away from the fixed abutment to cause the teeth of said lever to engage and move the ratchet wheel and also move the master gear through an arc until the front nose of the lever engages said adjustable abutment to effect movement of the drum to indicate starting position.

6. In a typewriter including a platen and a platen shaft mounted for rotatable paper feeding movement, a casing having a window provided at one edge with an index mark, means for indicating the approach of the end of the sheet around the platen including a sector behind said window and having visible scale marks thereon adapted to register with said index mark, said sector including a body loosely journaled on the platen shaft, an abutment within the casing, an arm extending from the body of the sector, a spring connecting said arm to the casing thereby to rotate said sector to normal position against said abutment, a two armed latch lever mounted on the shaft co-axially with the body of the sector and having a laterally offset tongue on one arm held against an edge of the sector body by a spring connecting the other arm with said upwardly extending arm on the body of the sector, a pinion fast on the platen shaft, a relatively large gear supported for free rotary movement on the inside of the casing and meshing with said pinion, and a pin projecting from the side of the gear adapted to engage the end of said arm of said latch lever having the tongue to impart angular movement to the sector as the pinion on the platen shaft moves said gear through the latter part of its cycle.

GIUSEPPE PREZIOSO.
